UNITED STATES PATENT OFFICE.

BERTRAND S. SUMMERS, OF PORT HURON, MICHIGAN.

AUTOMATIC METERING MACHINE.

Application filed November 6, 1922. Serial No. 599,252.

The apparatus forming the subject-matter of my invention is designed to record the weight of a body of more or less finely divided solid material fed to the device in a continuous stream and it is of particular advantage over other machines designed for this purpose in connection with the weighing of relatively coarse material, such as wood-chips used in making paper pulp, as it is not clogged or rendered inoperative or inaccurate by the passage therethrough of particles of considerable size. (It comprises a weighing beam supporting at its respective ends automatically dumping scale pans to which the stream of material is alternately fed. As each scale pan receives a predetermined load the beam is rocked to dump the same and the stream of material is shifted to the opposite pan which similarly rocks the beam when its load is completed, dumping the load and transferring the feed to the first mentioned pan. A preferred embodiment of my invention is described in the following specification taken in connection with the accompanying drawing forming a part thereof. It is to be understood, however, that the specific disclosure is for the purpose of exemplification only and that the scope of the invention is defined in the following claims in which I have endeavored to distinguish it from the prior art so far as known to me without, however, relinquishing or abandoning any portion or feature thereof.

In the drawing Fig. 1 is a side elevation of the preferred embodiment of my invention; Fig. 2 a similar view of a detail partly in vertical section; Fig. 3 an end elevation thereof; Fig. 4 a vertical section of a detail on an enlarged scale; and Fig. 5 a partial side elevation similar to Fig. 1 of a slightly modified form of the device.

In the views each element is identified by the same reference character wherever it occurs.

Referring now to the form of the invention shown in Figs. 1 to 4 inclusive, 6 is the scale beam, the knife edges 7 of which are fulcrumed at 8 on suitable seats carried on the standard 9. The scale pans 10 and 11 in this form of the apparatus are shown as rigidly connected by straps 12, 13 with the beam. Preferably the pans are in the form of deep triangular pockets the outer sides 15 of which are hinged at their top edges as at 16 so as to be capable of swinging open

to dump the contents of the respective pans. Each hinged side or door is provided with a latch-bar 17 pivoted to the door at 18 and notched at 19 to engage a pin 20 on a bracket 21 secured to the scale pan. When the latch-bar is in engagement with the pin 20 as seen at the right in Fig. 1 the pivoted side or door 15 is locked in closed position. A stop 23 secured to one of the standards projects into the path described by the latch bar when the beam tilts to lower the pan to which such bar is attached, so that as the pan or bucket descends the latch-bar is raised to free pin 20 from notch 19 and permit the door to drop open to the position shown at the left in Fig. 1. It will be understood that the stream of material is fed into the pan which is in the raised position and when the latter has received its full charge it swings downwardly and the door is released to discharge its contents.

The material from the hopper 25 or other feeding means is directed into the one pan or the other, according to which is in the raised position, by a pivoted chute 26. This chute is journaled between the standards at the upper ends thereof and above the beam as at 27, so that it may swing from the inclined position shown in Fig. 1 to a corresponding inclination in the opposite direction. As shown in Figs. 2 and 3, the journal of the pivoted chute 26 is provided with a fork 28, the bifurcated end of which engages a cylindrical boss 29 on a bracket 30 secured to the scale beam 6. As shown, the cylindrical boss 29 takes the form of a roller journaled on a bearing 31. The cylindrical boss or roller fits between the arms of the fork but has a slight play longitudinally of the latter, the construction being such that as the chute 26 tilts in one direction the beam tilts in the other.

It is obviously necessary that each pan be prevented from descending sufficiently to open its discharge door until it has received its complete load, and it is also desirable in the interests of rapidity and accuracy of operation that during the earlier portion of the operation of filling the material be fed to a pan rapidly and during the latter portion the stream of material be diminished to prevent an overcharge. I have provided for this mode of operation in the following manner: With this in view I have extended the shaft or journal of the chute beyond its bearing at one end and

secured thereto a depending arm 33 which carries a roller 34 at its lower end. The roller engages the cam face 35 of a vertically movable cam 36 which is pivoted on and supported by a lever 37. Lever 37 is pivoted at 38 upon arm 39. A link 40 connects the leg 41 of the cam with arm 39 so that the cam is capable of rising and falling with the lever 37 but is maintained in substantially horizontal position. In order to provide a slight lateral adjustment for cam 36, arm 39 is pivoted at 43 to standard 9 and its upper end 44 projects between set-screws 45, 46 tapped into suitable bosses on said standard. The face of the cam is formed with a slight central depression 60 for a purpose which will appear.

Obviously as whichever pan is being filled receives its load it tends to descend by gravity, but this tendency is resisted by the cam 35 acting through roller 34, arm 33, the journal of the reversible chute, arm 28, roller 29 and bracket 30. The descent of the cam is opposed by a series of weights 48 depending from the end of lever 37 opposite that which supports the cam. The weights 48 are to some extent offset by a weight 50 adjustable upon the right-hand arm of lever 37. By adjusting the last-named weight the load in a pan necessary to reverse the position of the scale beam and chute may be determined. Obviously as a load accumulates in a pan it ultimately reaches a point where the pressure of the roller 34 depresses the cam. The roller, therefore, rolls along the cam as the weight increases and acting through the beam and its connection to arm 33 overcomes the weight distribution on the lever 37, and after the roller 34 reaches the depression the resistance being thereby relieved it quickly passes the center. The further action of the weighted lever tending to raise the cam assists the swinging movement of arm 33, the reversible chute and the scale beam, so that the latter part of the reversing movement is fairly rapid and positive, easily providing the necessary force to unlatch the door of the full pan or pocket to permit the contents thereof to escape.

As heretofore stated, it is desirable that the rapid feed of material be checked as the load of a pan approaches completion, and for this purpose the construction of the machine is such that towards the end of a filling operation the reversible chute 26 gradually approaches the horizontal and as the delivery nozzle 25 is sufficiently close to the chute for the purpose, the material accumulating on the pivoted chute blocks the delivery of additional material from the nozzle temporarily. In order that the movement of the chute toward the horizontal may be gradual the arrangement of the weights is such that they are successively

taken up by the beam 37 as the left-hand end thereof is raised by the descent of the cam.

Referring now to Fig. 4 it will be noted that the uppermost weight 48^a is connected to the next in order, 48^b, by pins 54, 55 sliding in holes 56, 56, in weight 48^b and provided at their lower ends with heads 57, 57. Similarly, weight 48^b is connected with weight 48^c by pin 58 and weight 48^c 75 is connected to weight 48^d by pin 59, and so on. The initial downward movement of the cam 35 is therefore resisted only by the uppermost weight 48^a but as it continues to rise it successively picks up the other weights in order. Thus the chute 26 approaches the horizontal step-by-step until arm 33 reaches the central or vertical position, after which the reversal of position of chute 26 and the scale beam 6 is rapidly accomplished. Preferably the cam face 35 is cut away at 60 to permit the unopposed movement of the arm 33 through the central portion of its arc.

The operation of the device has been explained in connection with the description of the construction but may be summarized as follows: The material to be weighed is fed into the hopper 25 and any suitable means (not shown) may be provided for taking it away from the weighing machine. With the parts in the position shown in Fig. 1 the material to be weighed slides down chute 26 in a stream into the pocket or pan 11 at the right of the machine and accumulates therein. As the filling of this pan approaches completion the weight of the load exerted on the beam 6 and transmitted through parts 29, 28, 27, 33 and 34, depresses the cam 36, causing lever 37 to lift the weights 48 seriatim, until ultimately the load in the pan is sufficient to force the roller 34 past the center of the cam, after which the load on lever 37 operating through the cam assists to complete the reversal of the chute and beam. As the full pan descends the door is tripped and opened as heretofore described, permitting the contents to escape. As the other pan, 10, rises the door 15 thereof swings by gravity until the latch bar catches and holds it in closed position. As the chute 26 is now inclined downwardly toward the left the filling of the pan 10 takes place in the same manner as has already been described in connection with pan 11, and when pan 10 is filled the positions of the parts of the machine are reversed in a manner which will be readily understood.

As heretofore observed chute 26 is turned 125 toward the horizontal as the filling of a pan approaches completion and as it approaches the horizontal the flow of the material is slowly diminished until just prior to the completion of such a load as will shift 130

the scale beam and the pans carried thereby, the stream dwindles to a mere trickle.

By the operation of the scale substantially equal amounts of the chips or other divided matter are alternately dumped by the respective pans and may be carried away in any suitable conveyor provided for the purpose, or they may be permitted to accumulate in a suitable receptacle. By counting the reversals of the beam and multiplying the result by the weight constituting a single load, the total weight of material passing through the apparatus may be ascertained. The reversals may of course be counted by an observer. It is preferable however to record them on an automatic counter such as are in common use. At 82 Fig. 1 I have indicated a counter so located as to be actuated by the movement of the reversing chute 26.

20 As the rigid connection of the pockets 10 and 11 to the beam just described tends to move the center of gravity of each pocket outwardly as it is filled it is preferred for more accurate weighing to hang the pans on 25 the beam as shown in Fig. 5. For this purpose the beam 6 is provided with knife edges 70 and the supports 12', 13' are provided with a seat 71 engaging the knife edges, thus permitting the pan to swing. In order, 30 however, that the pan when empty may tilt outwardly to enable the door 15' to close by gravity, a weight 72 is adjustably mounted on a bar 73 projecting inwardly from the pocket or pan. Except in this respect 35 the construction is as described in connection with Figs. 1 to 4.

I claim:

1. In an apparatus of the class described 40 a support, a balanced beam fulcrumed on the support, pans carried at the respective opposite ends of the beam, a rocking chute pivoted above the beam and adapted to be tilted to discharge into either of said pans, connections between the beam and chute whereby when the beam is tilted in one direction the chute is tilted in the other, yielding means for holding the chute and beam when tilted in either direction but releasing them on the completion of a load in the elevated pan.

2. In a device of the class described a balanced scale beam, a pair of pans carried at the respective ends thereof, a support upon which the beam is fulcrumed, a pivoted arm, connections between the beam and arm whereby the tilting of the beam swings the arm, a cam arranged in the path of the arm, means for forcing the cam toward the pivot of the arm, the construction being such that 55 the cam opposes the movement of the arm from either extreme position toward its central position and assists the movement from said central position to an extreme position.

3. In a device of the class described a balanced scale beam, a pair of pans carried at

the respective ends thereof, means for conveying material in a stream to whichever pan is in the elevated position, a pivoted arm movable through a limited arc, connections between the arm and beam whereby 70 the tilting movement of the beam moves the arm, a cam having a substantially rectilinear face arranged at right angles to and movable in the central line of the arc of movement of said arm, means on the arm 75 engaging the bearing face of the cam and movable along the latter and yielding means normally exerting pressure on the cam toward the pivot of the arm.

4. In a device of the class described a balanced scale beam, a support on which it is fulcrumed, scale pans connected to the respective ends of the beam, an arm for yieldingly holding the beam in tilted position in either direction, said arm being fulcrumed 80 in said support, a connection between the arm and beam whereby the tilting movement of the beam under load swings the arm through a limited arc, an abutment on the arm, a cam having a rectilinear bearing edge arranged in a line perpendicular to the central radius of the arc of said arm and engaging the abutment on the arm, a lever to yieldingly support the cam against the pressure of the abutment on the arm, and 85 means for actuating the lever to force the cam toward the arm.

5. In a device of the class described a support, a balanced beam fulcrumed on the support, scale pans on the respective opposite ends of the beam, a pendulum arm, a pivot from which the pendulum arm hangs, the arm being adapted to swing through the arc upon opposite sides of the vertical line through its axis, a roller on the end of the 100 arm, a cam having a level upper edge engaged by the roller and along which the roller is adapted to travel, and means for yieldingly pressing the cam toward the pivotal support of the arm whereby the cam 105 opposes the downward swing of the arm in either direction.

6. In a device of the class described a balanced scale beam, a pair of pans carried at the respective ends thereof, a support upon 110 which the beam is fulcrumed, a pendulum arm pivoted on said support, connections between the arm and beam whereby the tilting of the beam moves the arm, a cam having a substantially horizontal bearing surface engaging the arm, a lever on which the cam is mounted for vertical movement and weights on the lever for forcing the cam into engagement with the arm.

7. In a device of the class described a balanced scale beam, a pair of pans on the respective opposite ends thereof, a support on which the beam is fulcrumed, a pendulum arm pivoted on the support and swinging 115 a substantially equal distance on op-

posite sides of a central vertical line, a cam having a horizontal surface engaging the arm and along which the arm travels, a lever supporting the cam, and a series of 5 pick-up weights on the lever.

8. In a device of the class described a balanced scale beam, a pair of pans on the respective opposite ends thereof, a support on which the beam is fulcrumed, a chute open 10 at its opposite ends, connections between the chute and beam whereby the tilting of the beam in one direction tilts the chute in the other, a pendulum arm secured to the chute and perpendicular thereto, a cam, an abutment on the arm engaging the cam and adapted to travel thereover, a lever supporting 15 the cam and pressing it against the abut-

ment on the arm, and a series of pick-up weights so connected to the lever as to be successively picked up thereby as the cam is 20 depressed by the abutment on the arm.

9. In a device of the class described, a balanced beam, pans rigidly attached to the respective opposite ends thereof to be tilted with the beam, a dumping door for each pan 25 hinged at its upper edge to the outer side of said pan and adapted to close and open therein, a latch normally holding said door closed, and a stop for engaging and lifting said latch when the bucket is lowered to 30 trip the latch and permit the door to swing open.

BERTRAND S. SUMMERS.
